UNITED STATES PATENT OFFICE.

EDWIN S. WOODS, OF CHICAGO, ILLINOIS.

DRAFT-RIGGING FOR RAILWAY-CARS.

SPECIFICATION forming part of Letters Patent No. 691,038, dated January 14, 1902.

Application filed January 7, 1901. Serial No. 42,425. (No model.)

To all whom it may concern:

Be it known that I, EDWIN S. WOODS, a citizen of the United States of America, and a resident of Chicago, in the county of Cook and State of Illinois, have invented certain new and useful Improvements in Draft-Rigging for Railway-Cars, of which the following is a specification.

The present invention relates to the double or tandem type of spring draft-rigging for railway-cars.

The object of the present invention is to provide a simple and effective connection between the tail-strap of the coupling-head and the centrally-arranged follower-plates of the tandem springs, all as will hereinafter more fully appear and be more particularly pointed out in the claims. I attain such object by the construction and arrangement of parts illustrated in the accompanying drawings, in which—

Figure 1 is a vertical longitudinal section of a draft-rigging embodying the present invention; Fig. 2, a horizontal section at line xx , Fig. 1.

Similar numerals of reference indicate like parts in both views.

Referring to the drawings, 1 1 represent the usual longitudinal draft-timbers, to which 30 the cheek-plates or draw-bar stop-castings 2 2 are secured in any usual and suitable manner, 3 the end sill, and 4 the transverse supporting stirrup-plate of a railway-car. Said cheek-plates or draw-bar castings 2 2 will be 35 of the usual counterpart construction secured to the draft-timbers in any usual manner, and each will be provided with a series of integral stops, lugs, or projections, comprising in the construction shown a central stop 5 and 40 front and rear end stops 6 and 7. Such series of stops, in connection with horizontal top and bottom flanges on the cheek-plates, form cavities in the opposing faces of the cheek-plates, which receive and guide the respective 45 ends of the series of follower-plates for the tandem-arranged springs 8 and 9, such follower-plates comprising in the construction shown the pair of central plates 10 and 11, arranged at and having bearing against the 50 opposite sides of the central stop 5, and the front and rear follower-plates 12 and 13, hav-

ing bearing against the front and rear stops 6 and 7, respectively.

14 is the usual draw-bar or coupling-shank, the rear end of which is adapted to have abutment against the forward follower-plate 12, as shown. 55

15 is the tail-strap, secured at its forward end in any usual and suitable manner to the rear end of the draw-bar 14 and preferably 60 formed of a single piece of metal having a substantially rectangular cross-section and bent into a stirrup form, as shown, and which tail-strap is extended back a sufficient distance to embrace both of the tandem springs 65 8 and 9 and have bearing, by means of its vertical portion 16, against the rear face of the rear follower-plate 13.

In the present invention the novelty involved comprises the formation of such tail-strap 15 intermediate of its length with lugs 70 17 17, that are preferably formed integrally on the opposing faces of the two parallel members of the said tail-strap, and which lugs will be of a length approximating that of the 75 central stops 5 of the cheek-plates 2 and adapted to rest between the central pair of adjacent follower-plates 10 and 11, so as to engage either one or the other of the same to effect a compression of one or the other of the 80 tandem springs under a pulling or a buffing strain, as the case may be.

With such improved construction a very simple, efficient, and economical connection is afforded in that the necessity of the usual 85 separate parts, with their attaching bolts and nuts, are entirely avoided and the same results attained in a much more effective manner by a single-piece formation capable of ready and economical manufacture. 90

The present invention is equally adapted by a mere duplication of the opposed and integrally-formed lugs on the opposing faces of the two parallel members of the draw-head tail-strap for use in connection with the ordinary triple spring tandem draft-rigging of 95 railway-cars in connection with a substantially like arrangement of parts.

Having thus fully described my said invention, what I claim as new, and desire to secure 100 by Letters Patent, is—

1. In a draft-rigging, the combination with

the draw-bar, its tandem springs and follower-
5 plates, of counterpart cheek-plates secured
to the longitudinal draft-timbers of the car
and provided with stop-lugs for the follower-
10 plates, and a draft-bar tail-strap formed by a
metal bar substantially rectangular in cross-
section and having permanently-attached and
intermediately-arranged lugs on the opposing
15 faces of the two parallel portions of the same,
which lugs are adapted to lie between the central
follower-plates to engage one or the other of
the same to compress one or the other of
the tandem springs in a buffering or pulling action
20 of the draw-bar, substantially as set forth.

2. In a draft-rigging, the combination with
the draw-bar, its tandem springs and follower-
25 plates, of counterpart cheek-plates secured
to the longitudinal draft-timbers of the car
and provided with stop-lugs for the follower-
30 plates, and a draft-bar tail-strap formed by a
metal bar substantially rectangular in cross-
section and provided with integrally-formed
lugs intermediately arranged on the opposing
35 faces of the two parallel portions of the same,
which lugs are adapted to lie between the central
follower-plates and adapted to engage
one or the other of the same to compress one
or the other of the tandem springs in a buffering
40 or pulling action of the draw-bar, substantially
as set forth.

3. In a draft-rigging, the combination with
the draw-bar, its tandem springs and follower-
45 plates, of counterpart cheek-plates secured
to the longitudinal draft-timbers of the car

and provided with stop-lugs for the follower-
50 plates and a draft-bar tail-strap formed by a
metal bar substantially rectangular in cross-
section bent into a single-piece stirrup form
and having integrally-formed lugs interme-
55 diately arranged on the opposing faces of the
two parallel portions of the same, which lugs
are adapted to lie between the central fol-
lower-plates to engage one or the other of the
60 same to compress one or the other of the tan-
dem springs in a buffering or pulling action of
the draw-bar, substantially as set forth.

4. In a draft-rigging, the combination with
the draw-bar, its tandem springs and follower-
65 plates, of counterpart cheek-plates secured
to the longitudinal draft-timbers of the car
and provided with stop-lugs for the follower-
70 plates, and a draft-bar tail-strap formed by a
metal bar substantially rectangular in cross-
section and having permanently-attached and
intermediately-arranged lugs on the opposing
75 faces of the two parallel portions of said strap
which lugs are adapted to lie between the fol-
lower-plates which separate one spring from
another and are further adapted to engage
80 one or more of the follower-plates thus eff-
ecting compression of one or more of the
draft-springs, substantially as set forth.

Signed at Chicago, Illinois, this 5th day of
January, 1901.

EDWIN S. WOODS.
